CONTOUR CUTTING ATTACHMENT FOR
TURNING LATHES

Charles F. Malzahn, Perry, Okla.

Application April 11, 1942, Serial No. 438,687

1 Claim. (Cl. 82—14)

My invention relates to the contouring of bodies having curved faces, and has among its objects and advantages the provision of an improved contour attachment for turning lathes.

In the accompanying drawing:

Figure 1 is a top plan view of a conventional turning lathe illustrating my invention applied thereto; and

Figure 2 is a sectional view taken along the line 2—2 of Figure 1.

In the embodiment selected for illustration, I make use of a conventional turning lathe 10 having a bed 12 on which the usual carriage 14 is adapted to travel longitudinally of the bed. Figure 1 illustrates a projectile body 16 having one end supported in the chuck 18 and its other end supported by the usual tailstock center 20. I also make use of the usual cross slide 22 which carries the tool holder 24 for presenting the tool 26 to the body 16 for shaping the face 28 of the body to its finished contour.

To the cross slide 22 is secured an arm 30 by bolts 32. Motion is imparted to the cross slide 22 through the medium of the arm 30 by reason of a contour slide or bar 34 bolted to the bar 36 of the usual taper bar mount. Bar 36 is supported by brackets 38 clamped to the bed 12 in the usual manner. In the instant case, the contour slide 34 is so contoured as to move the cross slide 22 transversely of the bed 12 through longitudinal movement of the carriage 14 on the bed for moving the tool 26 in a cutting path conforming to the contour of the slide 34. The slide 34 is contoured in conformity with the contour desired on the body 16.

Figure 2 illustrates a block 40 lying underneath the arm 30 and provided with a pin 42 threadedly secured therein. The sleeve 44 is provided with a shoulder 48 engaging the bottom face of the arm 30. A key 50 is formed on the shoulder 48 and extends into the slot 46 to restrain the sleeve from rotation. To the sleeve 44 is threadedly connected a handle 52 which acts as a nut through its engagement with the arm 30 to fixedly secure the sleeve 44 in different positions longitudinally of the arm 30.

Guide rollers 54 respectively engage the guide faces 56 on the contour bar 34, which guide rollers are mounted on bolts 58 through the medium

of roller bearings 60. The bolts 58 pass through openings in the block 40 and are made secure by nuts 62. Since the pin 42 is loosely related to the sleeve 44, the block 40 which carries the guide rollers 54 may rotate about the axis of the pin to accommodate the rollers 54 to the changing angle of the contour bar 34. Accurate adjustment of the contour bar 34 may be made through adjustment of the bar 36 on the brackets 38. For this purpose, the bar 36 is provided with slots 64 for the reception of fastening bolts 66 passing through the slots and threaded into the brackets 38.

In operation, the movement of the tool 26 conforms to the predetermined contour of the slide 34 so as to accurately shape the face 28 to the desired contour. The block 40 which carries the guide rollers 54 is fixedly secured against accidental displacement with respect to the arm 30 by reason of the shoulder 48 and the nut handle 52 which firmly secure the sleeve 44 to the arm 30. The pin 42 is firmly secured in the block 40 but is free to rotate in the sleeve 44. It will thus be seen that I have provided a contour attachment which may be associated with a conventional turning lathe to shape bodies to desired contours. A series of slides 34 is provided in conformity with variable shapes desired in the work.

Without further elaboration, the foregoing will so fully illustrate my invention, that others may, by applying current knowledge, readily adapt the same for use under various conditions of service.

I claim:

In a turning lathe having a bed, a carriage movable longitudinally of the bed and a tool carrying cross slide on the carriage; the combination of a contour slide fixedly related to the lathe, an arm secured to said cross slide and having a slot, a sleeve extending through said slot and having a shoulder engaging one side of the arm, a nut threaded on said sleeve engaging the opposite side of said arm to secure the sleeve against accidental movement on the arm, a body having a pin rotatably supported in said sleeve, and guide rollers on said body engaging said contour slide to move the arm and shift the tool in a path conforming to the contour of said contour slide.

CHARLES F. MALZAHN.
